UNITED STATES PATENT OFFICE.

ADOLPH A. THOMAS, OF NEW YORK, N. Y.

PHONOGRAPHIC SOUND REPRODUCER.

Application filed January 29, 1926. Serial No. 84,551.

This invention relates to the art of reproducing recorded sound, and its object is to provide a new and improved reproducer for phonographs or similar acoustic machines utilizing sound records for loud reproduction.

Briefly stated, the fundamental idea of my invention comprises a combined electro-mechanical reproducer as a single unit capable of reproducing from a record either mechanically through a diaphragm, or electrically through suitable electromagnetic mechanism. The device is readily adjusted for either method of reproduction. The advantages of this double-acting reproducer will presently become clear.

The acoustic reproduction of phonograph records has heretofore been carried out in two ways: first, mechanically by means of a diaphragm actuated by the record needle, the diaphragm vibrations being amplified through the tone arm and horn of the machine; second, electrically by causing the needle to operate a microphone or an electromagnetic device mounted on the tone arm for producing variable currents in a telephone receiver, which may be located in the phonograph cabinet or at a distance therefrom. In this electric reproduction, the tone arm is not utilized as an amplifier of sound waves, but the telephone receiver is acoustically connected with an amplifying horn or operates through a loudspeaking diaphragm. In phonographs utilizing mechanical reproduction, the maximum volume obtainable is necessarily limited by the maximum vibrations of the needle-actuated diaphragm as amplified through the tone arm and the horn. The volume of sound thus produced is usually sufficient for an ordinary room in a house or an apartment. But there are times when it is desirable to obtain a greater volume of reproduction from a record than is possible with a mechanical sound box—as, for instance, where a phonograph is played in a large hall or in the open. To meet this condition, it has been proposed to use an electric reproducer in which the needle operates a microphone or otherwise causes variable currents to flow in a telephone receiver. These currents may be amplified or stepped up to increase the volume of reproduction to the required degree. It is recognized that each method of phonographic sound reproduc-

tion—that is, the mechanical and the electrical—has its advantages: the mechanical method requires no batteries, circuits, etc., and the electrical method permits greater acoustic amplification, together with a finer regulation of volume.

In order to combine the advantages of mechanical and electrical sound reproduction in a single machine, I have provided a combined mechanical and electrical reproducer in a single unit adapted to be mounted on the tone arm. This double-acting unit has a single needle arm, a diaphragm mechanically actuated by the needle arm, and electromagnetic mechanism including a vibratory member connected to the inner end of the needle arm. The electric reproduction takes place independently of the diaphragm and so the operative connection between the needle arm and the diaphragm is separable. I provide means for selecting either the diaphragm or the electric mechanism for reproducing operation, and this selecting means is preferably controlled by a suitable finger piece outside the reproducer casing. The selecting means may also control the circuit connections of the electric reproducing mechanism.

The basic idea of my invention may be embodied in various constructions, of which two examples are illustrated in the accompanying drawings, where

Fig. 1 shows an interior face view of an electro-mechanical reproducer embodying my invention;

Fig. 2 is a cross-section on the broken line 2—2 of Fig. 1, the diaphragm being shown connected to the needle arm;

Fig. 3 represents a transverse cross-section on the broken line 3—3 of Fig. 1;

Fig. 4 is a view (partly broken away) similar to Fig. 2, but showing how the connection between the diaphragm and needle arm is broken;

Fig. 5 is a fragmentary detail view to illustrate how the adjustable selecting member, by means of which either the diaphragm or the electric reproducing mechanism is rendered operative, automatically closes the circuit of the electric mechanism when the diaphragm is disconnected;

Fig. 6 is a fragmentary face view of the lower portion of the reproducer casing to show the two positions of the selecting arm;

Fig. 7 illustrates an interior face view of

a modified construction, certain parts being shown in section on line 7—7 of Fig. 8;

Fig. 8 is a cross-section on the broken line 8—8 of Fig. 7, showing the needle arm connected to the diaphragm;

Fig. 9 is a transverse cross-section on line 9—9 of Fig. 7;

Fig. 10 shows a view (partly broken away) similar to Fig. 10, with the connection between the diaphragm and the needle arm broken; and

Fig. 11 is a fragmentary face view of the outer casing to indicate how the selecting knob should be turned for obtaining electric or mechanical reproduction.

In order to make the drawings as clear as possible, I have purposely exaggerated the dimensions and relative proportions of the different parts, which have been spread out considerably more than would be necessary in actual practice. These drawings are therefore not to be taken as shop drawings.

I shall first describe the construction shown on the first sheet, Figs. 1—6. A suitable casing C houses the various parts that comprise the interior working mechanism of the instrument. The casing C is here shown as consisting of a back plate 1, a cylindrical body section 2, and a front plate 3 or cover 3. These three parts may be separably connected, as by screws 4 engaging in peripheral bosses 5 of section 2. The casing may be constructed of non-magnetic metal, such as brass, aluminum, or aluminum alloy, or it may be shaped out of suitable composition material. The body section 2 is provided with a transverse annular flange 6 arranged to form a shallow recess or chamber 7, in which is mounted an acoustic diaphragm 8. This diaphragm is held rigidly clamped at its periphery in any practical way. For simplicity, I have shown diagrammatically a pair of non-metallic rings 9 between which the diaphragm is held for vibratory movement. The diaphragm is easily inserted in position through the open mouth of recess 7 before the back plate 1 is screwed on.

A magnet M, preferably of the permanent type, is supported within the casing. In the present instance, the magnet is secured to the annular flange 6 by screws 10 or otherwise. The flange 6 thus performs the double function of supporting the magnet and serving as part of the mounting for the diaphragm. By making the magnet of circular shape, as shown in Fig. 1, it is possible to obtain a maximum length of magnetic path in a small cylindrical casing. The ends of magnet M are turned forwardly at 11 for receiving pole pieces 12 of soft iron. These pole pieces are preferably cylindrical and are arranged in axial alignment to provide an airgap 13.

A needle arm 14 is pivotally mounted on

casing C by any practical means. For convenience, I have shown the casing provided with a pair of lugs 15, between which is supported a spring blade 16 of proper strength and resiliency. This spring passes through (or is otherwise rigidly connected to) the needle arm near the outer end thereof, which constitutes a needle holder 17. The tension of spring 16 permits the needle arm to vibrate transversely of the casing, as about a pivot, and the strength of the spring is amply sufficient to take up the longitudinal thrust on the needle arm in the playing of a record. The spring blade 16 thus serves as a pivot support for the needle arm and as a restoring or centering spring for the same. Any other suitable support for the needle arm may be employed. A slot 18 in section 2 of the casing permits the insertion of the needle arm into the casing and allows free vibration of the arm.

To the inner end of needle arm 14 is rigidly connected a coil 19, as by means of a strap or band 20 clamped tight around the coil. The ends of strap 20 are secured by a screw or rivet 21 to the needle arm. The coil is arranged to vibrate in the airgap 13 of the magnet. In the normal position of the needle arm, the coil 19 is substantially in axial alignment with pole pieces 12. The internal diameter of the coil should preferably be about the same as the diameter of the pole pieces. As the needle arm 14 vibrates, the coil 19 vibrates transversely of the pole pieces and thereby cuts the magnetic lines of force to generate electric current impulses. This will be understood by those skilled in the electrical art without the need of further explanation. By connecting the coil in suitable circuits these current impulses can be utilized to operate a loudspeaker or any other reproducing device. It is clear from Figs. 1 and 2 that the needle vibrations are transmitted to the coil in amplified ratio, so that the smallest vibrations of the needle point are sufficient to generate current impulses in the circuit of the coil. It is to be noted that there is no magnetic drag or load on the needle arm during vibration of coil 19.

In the broad aspect of my invention, the magnet M and coil 19 represent merely one of many practical forms of electric reproducing mechanism operated or controlled by the vibrations of the needle arm. I do not, therefore, intend to be limited to any particular construction of electric reproducing means, provided it is capable of operation independently of the diaphragm. One of the important features of my invention lies in the fact that the electric reproduction takes place without the diaphragm, which is used solely for mechanical reproduction through the tone arm on which the reproducer is mounted. To accomplish this re-

sult, I provide a readily separable and restorable connection between the diaphragm and the needle arm. This fundamentally novel idea may be mechanically carried out in various ways, one of which is shown by way of example in Figs. 1-6.

The diaphragm 8 is provided at the center with a U-shaped lug 22 carrying a cross-pin 23, to which is pivoted a lever 24. At a suitable point between its ends the lever 24 is formed with a slot 25 adapted to hook tightly over a pin 26 projecting laterally from the needle arm 14. The member 24 may be referred to as a hook or coupling. The parts should be so proportioned and designed that, when the slot 25 engages the pin 26, the diaphragm and needle arm are securely coupled together to vibrate as a unit. The free end 27 of coupling 24 extends into a cam slot 28 of a controlling member 29 pivoted on a pin or screw 30 carried by a U-shaped bracket 31. For convenience, the bracket 31 is secured by screws 32 to a transverse partition 33 formed as an enlargement of flange 6. The controlling member 29 has an arm 34, which extends through an arcuate slot 35 at the bottom of the casing and terminates in a finger piece 36. The outer end of arm 34 is preferably curved forwardly, so that the finger piece projects beyond the casing for easy manipulation.

The curvature of cam slot 28 in the hand-operated member 29 is such that, when this member is moved into the position shown in Fig. 1, the coupling 24 is forced down until the slot 25 hooks firmly over the pin 26 of the needle arm, as best shown in Fig. 2. The movement of finger piece 36 toward the left or "diaphragm" position (see Figs. 1 and 6) is automatically arrested when the arm 34 strikes the end of slot 35. A spring finger 37 may be used to engage the arm 34 frictionally and thereby retain the controlling member 29 in actuated position against possible rattling or accidental displacement. When the finger piece 36 is moved to the right or "electric" position, as indicated at 36' in Fig. 6, the cam slot 28 raises the coupling hook 24 out of engagement with pin 26, thereby entirely disconnecting the needle arm from diaphragm 8. Under this condition, the needle arm may be used to operate or control the electric reproducing mechanism without actuating the diaphragm. The disconnection of the diaphragm from the needle arm during electric reproduction is one of the basic features of my invention. It makes it possible to use the same horn in a phonograph cabinet for amplifying the mechanical as well as the electrical reproduction. The diaphragm, it goes without saying, amplifies through the tone arm which connects with the horn. The current impulses generated

by the electric reproducing means operate or control a loudspeaking telephone receiver which may be acoustically connected with the same horn as the diaphragm on the tone arm. This requires that the diaphragm must not vibrate during the operation of the electric reproducing mechanism. Of course, if the current impulses generated by coil 19, or whatever electromagnetic device may be operated by the needle arm, are conveyed to a loudspeaker situated at a distance beyond the hearing of a person near the phonograph cabinet, it is possible to have mechanical and electrical reproduction at the same time, provided the circuit through coil 19 remains closed during the operation of the diaphragm. While the instrument of my invention is capable of such use, the primary object is to provide a combined mechanical and electrical reproducer in which the electrical reproduction can take place without operating the diaphragm.

I shall now direct attention to the enlargement 28' provided at one end of cam slot 28. The width of this slot is such that the end 27 of coupling 24 engages the walls of the slot in a snug fit during the movement of cam member 29 in either direction. For this purpose, the walls of slot 28 are preferably formed on a slant, as indicated in Figs. 1 and 5, to accommodate the pivotal movements of the coupling arm 24 without lost motion. Now, when the controlling member 29 has almost reached the end of its movement to connect the diaphragm with the needle arm, the projecting end 27 of the coupling arm passes out of the cam slot 28 into the enlargement 28'. In other words, after the member 29 has been operated by finger piece 36 to connect the needle arm with the diaphragm, the member 29 is automatically disconnected from the connecting piece 24. This is necessary in order to permit free vibration of the diaphragm and needle arm without interference by the controlling member 29. The other end of cam slot 28 does not require an enlargement similar to 28', because the member 29 may remain connected with the coupling 24 when the needle arm is disconnected from the diaphragm. This will be understood from Fig. 4.

So that no unnecessary waste of battery current may occur during intervals in which the electric reproducing mechanism is not used, I provide means for automatically opening suitable switch connections in the electric reproducer circuit when the instrument is operated for mechanical reproduction through the diaphragm. In the present embodiment I have shown a pair of switch contacts 38 and 39 mounted on an insulating bracket arm 40, which is secured to the U-shaped frame 31, or is otherwise supported in the casing. To the contacts 38 and

39 are connected the end conductors 41 of coil 19. Also, a pair of leads 42 are connected to contacts 38 and 39. These contacts are normally open. For this purpose, 5 they are preferably made of spring metal and their inherent resiliency normally holds them apart, as indicated in Fig. 3. The selecting member 29 carries an insulated cam projection 43 arranged to engage the contact 38 and force it against the contact 39 when the member 29 disconnects the needle arm from the diaphragm. This position of member 29 is shown in Fig. 5. It is understood, of course, that the finger piece 36 15 is not moved into the "electric" position 36' (see Fig. 6) unless and until the instrument is to be used for electric reproduction. In the broader aspect of my invention, the contacts 38 and 39 represent a switch in any 20 part of the electric reproducing circuit or system of which the coil 19 is an element. The switch 38-39 may be omitted to permit simultaneous electrical and mechanical reproduction.

25 The reproducer casing is operatively mounted on a tone arm 44, as by means of a hub 45 projecting from the back plate 1 of the casing. A set-screw 46, engaging in a slot 47 of hub 45, determines the correct position of the reproducer on the tone arm. The leads 42 are connected to binding posts 48 mounted on an insulated disk 49 attached to the back plate of the casing, as illustrated in Fig. 2. Only one of the 30 binding posts 48 is shown, but the construction is clear enough. Conductors 50 are separably connected to the binding posts 48 and lead through an opening 51 in hub 45 into the tone arm, so as to be concealed from view. The conductors 50 are properly connected in circuit, as will be understood without further description. To remove the 35 reproducer casing, it is only necessary to disconnect the conductors 50 from binding posts 48 and loosen the set-screw 46.

The modification of Figs. 7-11 differs from the construction of the preceding figures in the mechanism for selectively connecting and disconnecting the diaphragm 50 and needle arm. To avoid useless repetition in explaining Figs. 7-11, I shall omit a detailed description of all those parts that were previously described in reference to Figs. 1-5. It will be sufficient to mark 55 corresponding parts in the two sets of views with like reference characters. The diaphragm 8 in Figs. 7-10 is provided at the center with a screw-plug 52. The needle arm 14 has rigidly secured to it a screw-threaded 60 socket 53 in which is supported a screw 54 provided at its outer end with a pinion 55. The screw 54 is adapted to engage in the screw-threaded plug 52. On the front plate or cover of the casing is formed a bearing 65 56 in which is journaled an arbor or stub-

shaft 57. A suitable finger piece 58, here shown as a knob, is fixed to the outer end of shaft 57, and to the inner end of this shaft is connected a gear 59 arranged to mesh with pinion 55. The gear 59 does not have a complete circle of teeth, but has a cut-away or mutilated section 60 which does not engage the pinion 55, for a purpose that will presently be explained. A fixed stop 61 on the casing engages a stop 62 on gear 59 to limit the movement of the latter in either direction.

The operation of the selective connecting mechanism of Figs. 7-10 is as follows: Let us assume that the screw 54 is in engagement with the plug 52 of the diaphragm, so that the needle arm is operatively connected with the diaphragm for mechanical reproduction. This is the position of the parts shown in Figs. 7, 8 and 9. 85 It will be observed that the gear 59 is out of contact with the pinion 55 of the connecting screw 54, thus permitting free vibration of diaphragm and needle arm as a single member without interference by the controlling gear. Now, if the operator desires electric reproduction, the knob 58 is turned in the direction indicated by arrow *a* in Fig. 11. After a slight preliminary turn, the teeth of gear 59 engage the pinion 55 and rapidly rotate the screw 54 in a clockwise or right-handed direction. The screw 54 being left-handed, this turning of the screw moves the same out of plug 52 to disconnect the needle arm from the diaphragm. When 100 the lug 62 on gear 59 strikes one side of the fixed stop 61, the screw 54 is in the position shown in Fig. 10 and further movement of the knob 58 in the direction *a* is prevented. By providing an opening 55' in 105 the cover of the casing in alignment with pinion 55, the width of the casing may be reduced without danger of the pinion striking the casing when the needle arm vibrates. The pinion 55 is long enough to permit continued engagement with the gear 59 during 110 the axial movement of screw 54 from its connecting position in Fig. 9 to its withdrawn position in Fig. 10. To connect the needle arm again with the diaphragm, the 115 knob 58 is turned in the direction of arrow *b* in Fig. 11, whereby the pinion and screw are rotated counterclockwise until the lug 62 of gear 59 strikes the other side of stop 61. The screw 54 is then in the connecting 120 position shown in Fig. 9, and the gear 59 is fully disconnected from the pinion. It may be found desirable to insert a pad 63 of hard rubber or other yieldable material in the bottom of plug 52 to produce a final 125 jamming effect as the screw 54 reaches home and presses against the pad. This produces a tight solid joint between diaphragm and needle arm, and yet it is a joint that is easily separated by a mere turn of knob 58. To 130

prevent possible rattling or looseness of screw 54 when it is in disconnecting position, the socket 53 may be provided with a lining 64 of hard rubber or like material, which 5 presses into the screw-threads and thereby holds the screw against working loose during the vibrations of the needle arm. It is understood that the gear ratio between the members 55 and 59 is so related to the pitch 10 and number of screw-threads in screw 54, that one turn of gear 59 moves the screw into and out of connecting position. I have not attempted to indicate these transmission ratios with mathematical precision in the 15 drawings.

The operator can readily tell, by simply feeling the knob 58, whether the diaphragm and needle arm are connected or disconnected. For instance, looking at Fig. 11, if 20 the operator tried to turn the knob clockwise and found it locked against movement in that direction, he would know at once that the needle arm was connected to the diaphragm and that, therefore, the instrument 25 was in condition for mechanical reproduction. Conversely, if the operator found that he could not turn the knob in the direction of arrow *a* in Fig. 11, he would know that the instrument was set for electric reproduction. 30

The automatic switch control described in connection with Figs. 1-5 may obviously be embodied in Figs. 6-10, but I have not considered it necessary to encumber the 35 drawings with a superfluous duplication of this feature.

It will be seen from the foregoing description that I have devised a combined mechanical and electrical sound reproducer in a 40 single unit capable of ready adjustment for either method of reproduction. The same horn in the cabinet containing the reproducer may be used for amplifying both the mechanical and the electrical reproduction. 45 This is made possible because the electric reproduction takes place independently of the diaphragm and without vibration thereof. As far as I am aware, this characteristic feature of my invention is fundamentally 50 new.

Although I have shown and described certain constructions, I have done so for the sake of explaining in detail two embodiments which at the present time serve best 55 to express my ideas, and not by way of restriction or limitation. It is manifest that the various features of my invention may be carried out in other ways than herein set forth without departing from the scope of 60 the invention as defined in the following claims.

What I claim as my invention is:

1. A sound reproducer comprising a mechanically actuated arm, and mechanical 65 and electrical sound reproducing means

adapted to be operated by said arm independently of each other.

2. A phonograph reproducer having a needle arm, a diaphragm actuated by said arm, and electric reproducing mechanism 70 also operated by said arm independently of said diaphragm.

3. A phonograph reproducer unit having a diaphragm and electric reproducing mechanism, means for selecting either said diaphragm or said mechanism for reproducing operation, and a switch automatically operated by the movement of said selecting means to close an electric circuit of said mechanism when the latter is selected for reproducing 80 operation, said switch being automatically opened when the diaphragm is selected for operation.

4. In a phonograph reproducer, a diaphragm, a needle arm, an adjustable member 85 for connecting and disconnecting said diaphragm and arm, and means for operating said member, said operating means being automatically disconnected from said member when the latter has been moved into connecting position. 90

5. A phonograph reproducer unit having a needle arm, a diaphragm actuated by said arm, electric reproducing mechanism, and means for operating said mechanism without 95 actuating said diaphragm.

6. A phonograph reproducer having a needle arm, a diaphragm actuated by said arm, electric reproducing mechanism also operated by said arm, and manually adjustable means for rendering the connection between said arm and said diaphragm inoperative during the operation of said electric mechanism. 100

7. In a phonograph reproducer having a 105 casing, a diaphragm in said casing, a needle arm, an adjustable connecting element between said diaphragm and said arm for connecting and disconnecting those two parts, and a member operable from outside said casing for adjusting said element into connecting and disconnecting positions. 110

8. In a phonograph reproducer having a 115 casing, a diaphragm in said casing, a needle arm, an adjustable connecting element between said diaphragm and said arm for connecting and disconnecting those two parts, and a member operable from outside said casing for adjusting said element into connecting and disconnecting position, said 120 member being separable from said element when the diaphragm and needle arm are connected.

9. In phonographic reproducing apparatus, a combined mechanical and electrical reproducer adapted to be mounted on a tone arm for operation through a record-playing needle, and means for preventing reproduction through the tone arm during the electrical reproduction. 125

10. In sound reproducing mechanism, a diaphragm and a telephone transmitter, a mechanically vibrated member for operating said diaphragm and said transmitter, and means to prevent operation of said diaphragm during the operation of said transmitter by said member. 60
11. A phonograph reproducer comprising a casing, a needle arm pivoted to said casing, a diaphragm mounted in said casing, an adjustable coupling between said arm and said diaphragm, a movable finger piece projecting outside said casing, a member operable by said finger piece to move said coupling 65 into and out of operative position, means whereby said member does not interfere with the operations of the diaphragm, and electric reproducing mechanism in said casing, said mechanism including a vibratory member connected to said arm. 70
12. A phonograph reproducer comprising a casing, a needle arm pivoted to said casing, a diaphragm mounted in said casing, an adjustable coupling between said arm and said diaphragm, a movable finger piece projecting outside said casing, a member operable by said finger piece to move said coupling into and out of operative position, means whereby said member is automatically disconnected from said coupling when the latter is operated to connect the diaphragm to the needle arm, and electric reproducing mechanism in said casing operated by said arm. 80
13. A phonograph reproducer comprising a casing, a needle arm pivoted to said casing, a diaphragm mounted in said casing, a pivoted hook for operatively connecting said arm and said diaphragm, a pivoted member having a cam slot, an extension on said hook arranged to engage in said slot, whereby operation of said cam member moves said hook into connecting and releasing positions, said cam slot terminating at one end in an enlargement for freely receiving said extension when the hook connects the diaphragm with the arm, so that said cam member is disconnected from said hook when the needle arm actuates the diaphragm, a slide- 90 able finger piece projecting from said casing for operating said cam member, and a telephone transmitter mounted in said casing and having a vibratory member connected to said arm. 100
14. In a combined mechanical and electrical sound reproducer, a diaphragm, an acoustically actuated arm for operating said diaphragm, a readily separable and restorable connection between said parts, and electric reproducing mechanism operated by 60 said arm. 110
15. In a phonograph reproducer having a casing, a diaphragm in said casing, a needle arm, an adjustable connecting element between said diaphragm and said arm for connecting and disconnecting those two parts, and a rotary member operable from outside said casing for adjusting said element into connecting and disconnecting positions. 70
16. In a phonograph reproducer having a casing, a diaphragm in said casing, a needle arm, an adjustable connecting element between said diaphragm and said arm for connecting and disconnecting those two parts, a member operable from outside said casing for adjusting said element into connecting and disconnecting positions, and means whereby said member is automatically disconnected from said element when the latter has been moved into connecting position. 75
17. A phonograph reproducer unit having a diaphragm and electric reproducing mechanism, and means for selecting either said diaphragm or said mechanism for reproducing operation. 85
18. A phonograph reproducer comprising a casing containing a diaphragm and electric reproducing mechanism, and an adjustable finger piece outside said casing for placing either said diaphragm or said mechanism in condition for reproduction. 90
19. A phonograph reproducer having a needle arm, a diaphragm actuated by said arm, electric reproducing mechanism including a coil, means for operating said mechanism through said arm independently of said diaphragm, and means whereby the circuit of said coil is automatically broken 100 when the diaphragm is operatively connected to said arm. 105
20. In a sound reproducer, a mechanically actuated diaphragm, electric reproducing mechanism adapted to be operated independently of said diaphragm, said mechanism including a coil, a switch for controlling the circuit of said coil, an adjustable connecting device for selecting either said diaphragm or said mechanism for reproducing operation, and means controlled by said device for automatically opening said switch when the diaphragm is connected for operation, said switch being automatically closed when said device is adjusted to obtain re- 110 production through said mechanism. 115

ADOLPH A. THOMAS.
